CLAIM

The ornamental design for an agitating rod and impeller of agitator assembly of a washing machine, as shown and described.

DESCRIPTION

FIG. 1 is a front view of the agitating rod and impeller of agitator assembly of a washing machine, showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof;

FIG. 8 is another perspective view thereof; and,

FIG. 9 is a partial enlarged view of an area labeled 9 in FIG. 8.

The broken lines in the drawings depict portions of the agitating rod and impeller of agitator assembly of a washing machine that form no part of the claimed design.

1 Claim, 9 Drawing Sheets
